(57) **CLAIM**

The ornamental design for a dual magnification table mirror, as shown and described.

DESCRIPTION

FIG. 1 is a front elevation view of a dual magnification table mirror according to the present invention.

FIG. 2 is a left side elevation view thereof.

FIG. 3 is a right side elevation view thereof.

FIG. 4 is a rear elevation view thereof.

FIG. 5 is an upper plan view thereof.

FIG. 6 is a lower plan view thereof.

FIG. 7 is a left side view thereof, showing a mirror frame thereof rotated with respect to a mirror frame support ring thereof; and,

FIG. 8 is a front elevation view thereof, showing a mirror frame support ring thereof swivelled with respect to a base thereof.

The broken lines are for illustrative purposes only and form no part of the claimed design.
